UNITED STATES PATENT OFFICE

2,503,503

DOOR BAR-BOLT

Van McGaffey, New York, N. Y.

Application September 22, 1947, Serial No. 775,502

2 Claims. (Cl. 292—150)

1

The present invention relates to new and useful improvements in sliding locking bolts for doors and for other purposes where a bolt of this character may be used.

An important object of the invention is to provide novel means for actuating the bolt into and out of locked position from either side of a door.

A further object is to include as a part of the construction of the sliding bolt, a locking bar for securing the hinged edge of the door from becoming forced open and in which the locking bar is permanently engaged with the door casing while the sliding bolt is locked and unlocked and whereby the door is free to open without interference by the locking bar when the sliding bolt is unlocked.

Another object is to provide a device of this character of simple and practical construction, which is strong and durable, easy to install in operative position, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a view in elevation showing the locking bolt and bar secured in locked position to a door.

Figure 2 is a longitudinal sectional view taken on a line 2—2 of Figure 1.

Figure 3 is an enlarged longitudinal sectional view taken on a line 3—3 of Figure 1.

Figure 4 is an enlarged fragmentary longitudinal sectional view taken on a line 4—4 of Figure 1.

Figure 5 is a longitudinal sectional view taken on a line 5—5 of Figure 4, and

Figure 6 is a vertical transverse sectional view taken on a line 6—6 of Figure 5.

Referring now to the drawings in detail, wherein for the purpose of illustration I have disclosed a preferred embodiment of my invention, the numeral 5 designates an elongated housing of rectangular shape in cross section and open at each end. Angle brackets 6 are suitably secured to the sides of the housing for attaching the housing in a horizontal position to the inner surface of a door 7. The rear surface of the housing is formed with a longitudinal slot 8.

A bolt 9 is slidably mounted in one end of the housing to project therefrom, the inner end 10 of the bolt being hollow and having an open rear side opposed to the slot 8, as shown in Figure 6.

A pair of pins 11 project rearwardly from the inner front side of the hollow end 10 working in vertical slots 12 in a locking plate 13 slidably

positioned for vertical movement against the inner front side of the hollow end of the bolt. The plate 13 is formed at its lower edge with a locking tongue 14 working in an opening 15 in the bottom of the hollow end 10 to selectively engage longitudinally spaced apart openings 16 and 17 in the lower edge of housing 5, when one of the latter is aligned with opening 15. The upper edge of plate 13 is formed with a rearwardly projecting flange 18 above which is positioned a leaf spring 19 secured at one end to the top of the hollow end 10 and having its free end bearing against the top of the flange to hold the tongue 14 in engagement in either the opening 16 or in the opening 17.

The outer surface of housing 5 is formed with a longitudinal slot 20 having vertical re-entrance slots 21 and 22 at each end and extending downwardly therefrom. A handle 23 is positioned outwardly at the front of the housing 5 and provided with a stem 24 working in the slot 20, the inner end of the stem being suitably secured to plate 13.

A conventional key operated lock 25 is secured to the outer surface of the door and includes a barrel 26 recessed in the door and a shaft 27 extending inwardly therefrom. A combined cam and interrupted gear 28 is secured to shaft 27 and comprises a disk eccentrically secured to the shaft and having gear teeth 29 formed at one edge and a diametrically opposed flat edge 30 with cam humps 31 and 32 between the gear teeth and flat edges at each end of the teeth. The combination cam and gear 28 engages a rack bar 33 on the under side of flange 18, the rack bar being held in engagement therewith by the leaf spring 19.

In the operation of the sliding bolt 9 from the inside of the door, the handle 23 is moved longitudinally of the housing 5, which likewise moves the bolt 9 in a similar direction to engage the outer end of the bolt in a keeper 34 in the door jamb 35 to lock the door, or to retract the bolt to unlock the door. At the end of either its locking or unlocking movement the handle is moved downwardly into the vertical slots 21 or 22, as the case may be, which enters the locking tongue 14 in either the opening 16 or 17 to thus secure the bolt in either its locked or unlocked position. The spring 19 holds the tongue 14 downwardly against accidental raising movement.

To lock or unlock the bolt 9 from outside the door, a proper key is inserted in lock 25 to rotate shaft 27 and combined cam and gear 28. The initial rotation of the shaft will cause one of the cam humps 31 or 32 to raise the flange 18 and locking plate 13 to release tongue 14 and a further continued rotation of the shaft will move the gear teeth 29 into engagement with the rack bar 33 to slide the plate 13 and bolt 9 connected

thereto into either its projected or retracted position in the keeper to either lock or unlock the door, in accordance with the direction of rotation of the shaft 27 and disk 29.

A locking bar 36 is mounted in the opposite end of housing 5 and is secured in outwardly adjusted position by a set screw 37. The outer end of the locking bar is engaged in a keeper 38 secured in the door casing 39 at the hinged edge of the door, the keeper 38 having an arcuate chamber 40 therein to accommodate the movement of the bar during opening and closing of the door. The locking bar 36 secures the door from being forced open at its hinged edge while permitting free swinging movement of the door when opening or closing the same.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A door securer comprising a casing secured to a door, a bolt slideable in the casing, a vertically slideable locking plate carried by the bolt, inter-engaging locking means between the lower edge of the plate and the casing to hold the bolt in either its projected or retracted position, and means positioned at least at one side of a door for actuating the plate, said last named means

including a rack bar carried by the plate and an ovate gear journaled in the door and engaging the rack bar to release or lock the plate by a raising and lowering movement thereof and to project and retract the bolt.

2. A door securer comprising a casing secured to a door, a bolt slideable in the casing, a vertically slideable locking plate carried by the bolt, inter-engaging locking means between the lower edge of the plate and the casing to hold the bolt in either its projected or retracted position, and means positioned at least at one side of a door for actuating the plate, said last named means including a rack bar carried by the plate, and a revolute member having a cam initially raising the plate upon rotation of said member and gear teeth engaging the rack bar to slide the plate and the bolt horizontally upon a subsequent rotation of the member.

VAN McGAFFEY.
